[57] CLAIM

The ornamental design for a towel dispenser, as shown
and described.

DESCRIPTION

FIG. 1 is a top, front, and left side perspective view of
a towel dispenser showing my new design, the broken-
line disclosure of a portion of a wall being for illustra-
tive purposes only and forming no part of the claimed
design;

FIG. 2 is an enlarged front elevational view thereof;
FIG. 3 is an enlarged top plan view thereof;
FIG. 4 is an enlarged rear elevational view thereof;
FIG. 5 is an enlarged left side elevational view thereof,
the right side being a mirror image of that shown; and,
FIG. 6 is an enlarged bottom plan view thereof.
